Primary Examiner — Karen E Eldridge Powers

(74) Attorney, Agent, or Firm — Volk & McElroy, LLP;
Michael D. Volk, Jr.(57) **CLAIM**

The ornamental design for a hair brush, as shown.

DESCRIPTION

FIG. 1 is a top, rear and right side perspective view of a hair brush showing my new design.

FIG. 2 is a top, front and left side perspective view thereof.

FIG. 3 is a rear elevation view thereof.

FIG. 4 is a right side elevation view thereof. The left side elevation view is the same as the right side elevation view.

FIG. 5 is a front elevation view thereof.

FIG. 6 is a top plan view thereof; and,

FIG. 7 is a bottom plan view thereof.
